UNITED STATES PATENT OFFICE.

ELDER MULLAN, OF ROME, ITALY, ASSIGNOR TO WILLIAM J. FEELEY, OF PROVIDENCE, RHODE ISLAND.

DESIGN FOR A MEDAL.

40,821.

Specification for Design.

Patented Aug. 16, 1910.

Application filed April 14, 1910. Serial No. 555,549. Term of patent 14 years.

To all whom it may concern:

Be it known that I, ELDER MULLAN, a citizen of the United States, residing at Rome, Italy, have invented a new, original, and ornamental Design for a Medal, reference being had to the accompanying drawings.

Figure 1 is a view of the obverse side of the medal, showing my design. Fig. 2 is a view of the reverse side of the same.

I claim—
The ornamental design for a medal, as shown.

ELDER MULLAN.
